Primary Examiner — W. A. Teddy Falloway(74) Attorney, Agent, or Firm — Faegre Drinker Biddle & Reath LLP(57) CLAIM

The ornamental design for a packaging container for foodstuff as shown and described.

DESCRIPTION

The patent or application file contains at least one drawing executed in color. Copies of this patent or patent application publication with color drawing(s) will be provided by the Office upon request and payment of the necessary fee.

1.1 : Perspective

1.2 : Front

1.3 : Back

1.4 : Left

1.5 : Right

1.6 : Top

Features only visible from the bottom of the packaging container for foodstuff form no part of the claimed design.

1 Claim, 6 Drawing Sheets
(6 of 6 Drawing Sheet(s) Filed in Color)
